VENTILATING APPARATUS

Francis C. Kilb, Larchmont, N. Y., assignor to
 American Radiator Company, New York, N. Y.,
 a corporation of New Jersey

Application July 3, 1936, Serial No. 88,707

16 Claims.

(Cl. 98—94)

My invention relates to ventilating apparatus, and more particularly to apparatus of this type which is adapted for installation in windows of rooms, and which operates to admit fresh, filtered air into the room and/or to exhaust stale room air to the outside atmosphere.

My invention has for one of its objects to provide ventilating apparatus which is of improved construction and arrangement of parts, and which, when installed in a window opening, is neat and pleasing in appearance, and can be easily and quickly serviced.

A further and more specific object is to provide an improved form of casing structure for ventilating apparatus, which is divided into two parts, one of which is fixedly secured in position over the window sill, and the other of which can be readily removed from and replaced on the first part without disturbing the mounting of the first part in the window; whereby the interior working parts may be inspected and minor repairs made thereto without removal from the casing, or whereby the working parts may be readily removed from the casing and the second part replaced on the first part and major repairs made to the interior working parts at a remote service station.

Without imposing any limitation on the invention in its broader aspects, a still further object is to provide an improved form of casing structure for ventilating apparatus which is adapted to be mounted centrally of an opening defined by a partially raised window sash and a window sill, with a front half inside of the room and a rear half outside of the room; and which, when mounted in position, effectively conceals the connection thereto of the side filler blocks and effectively provides for the drainage of rain water from the exposed parts thereof disposed outside of the window.

The invention consists in the novel construction and combination of parts, to be more fully described hereinafter, and the novelty of which will be particularly pointed out and distinctly claimed.

In the accompanying drawings, to be taken as a part of this specification, I have fully and clearly illustrated a preferred embodiment of my invention, in which drawings—

Fig. 1 is a vertical transverse sectional view showing one preferred form of my apparatus, the section being taken on the line 1—1 of Fig. 2;

Fig. 2 is a horizontal plan view showing my improved form of ventilating apparatus as installed centrally within a window opening, certain parts

being broken away to show the interior of the ventilator casing;

Fig. 3 is an end elevation of my improved form of ventilating apparatus illustrating its division into a base unit and a removable cover unit, and showing the cover unit as removed from the base unit;

Fig. 4 is a rear elevation of the removed cover unit, showing the interior construction thereof;

Fig. 5 is a front elevation of the base unit with the cover unit removed;

Fig. 6 is a fragmentary horizontal sectional view illustrating the means at the ends of the ventilator for securing the cover unit to the base unit;

Fig. 7 is a fragmentary perspective view showing more in detail the base unit and the removable cover unit and the means for detachably connecting the two together, the removable inner working parts of the casing and certain of the fixed parts being omitted; and

Fig. 8 is an enlarged fragmentary sectional view through the lower front portion of the ventilating apparatus, as viewed in Fig. 1, and showing the detail structure of the operating means for the motor switch.

Referring now in detail to the construction illustrated, the reference numeral 10 indicates a sill of a window, the numeral 11 a lower sill rail of a window sash 12, and the numeral 13 the window jambs. A ventilator 14 is arranged centrally within the opening defined by the lower sill rail 11 and the window sill 10, with its rear part extending outside of the window and its front part extending into the room. Filler blocks 15 are arranged at the ends of the ventilator, and serve to close the spaces between the ends of the ventilator and the window jambs 13. The blocks 15 are the same height as the casing; and, when the window sash is lowered against the top of the casing, the lower surface of the sill rail has a sealing engagement with the top surfaces of the filler blocks as well as the top of the ventilator.

The ventilator comprises a casing 16 including a front wall 17, a rear wall 18, a top wall 19, a bottom wall 20, and end walls 21. The rear wall 18 is provided with an inlet opening 22 extending for the full length of the casing, and having fixed louvers 23 positioned therein for preventing the entrance of rain or snow. A filter 24 is removably mounted in vertical guides 25 and extends across the forward side of the opening 22, and thereby serves to eliminate dust, foreign particles and the like from the entering air. The front wall 17 is provided with a louver-controlled outlet opening 55

26 extending for substantially the full length of the casing. Likewise, the forward part of the top wall 19 is provided with louver-controlled outlet openings 27.

5 An upright partition 28 extends lengthwise of the casing and divides the latter into a rear inlet chamber 29 communicating through the filter 24 and inlet opening 22 with the outside atmosphere, and into an outlet chamber 30 communicating 10 through the outlet openings 26 and 27 with the room. A motor-driven blower unit 31 is removably mounted within the inlet chamber 29 and serves to force air from the inlet chamber through 15 openings 32 in the partition 28 and into the outlet chamber 30, from whence it passes through the openings 26 and 27 and into the room. The motor-driven blower unit 31 is fixedly secured to a supporting base member 33, and the latter is supported by the bottom wall 20 and is positioned 20 between longitudinally extending parallel guides 34 and 35 suitably spot welded to the bottom wall 20. The base member 33, motor-blower unit 31 and partition 28 are all secured together and may 25 be installed and removed as a unit. The partition 28 is secured by suitable screws 36 to the upper part of the motor-blower unit 31 and by screws 37 to brackets 38 extending forwardly from and carried by the base member 33. Suitable wing nuts 39 and bolts 40 passing through 30 the bottom wall 20, serve to secure the base member 33 to the bottom wall of the casing.

Each of the end walls 21 of the casing is divided along an upright central line into a front section 45 and a rear section 46, the division lines 35 being shown as vertical and as being the same distance from the plane of the front wall 17. The top wall of the casing is divided along a longitudinal line into a front section 47 and a rear section 48, the line of division between the two 40 sections of the top wall being in substantially the same vertical plane as the lines of division between the two sections of the end walls, and the ventilator casing being so arranged with respect to the window sash that such plane is just forward of the plane of the window sash, as can be clearly seen from an examination of Figs. 1 and 2. The rear section 48 of the top wall is 45 hinged as indicated at 49 to the rear wall 18, and when the window sash is raised, the rear section 50 may be thrown back and the filter 24 readily removed and replaced.

The bottom wall 20, the rear wall 18, the rear sections 46 of the end walls 21 and the rear section 48 of the top wall 19, are all secured together to form a base unit 50 which is firmly secured 55 in position within the window opening. To this end, straps 51 are suitably spot welded to the bottom wall at each end thereof, and screws 52 passing through openings in the straps and through the window sill 10 serve to anchor the bottom wall 60 in position. Vertical jack screws 53 extending through the bottom wall at the rear of the ventilator, engage the outer sloping part of the sill 10 and serve to support the rear part of the 65 ventilator.

The front wall 17, the front sections 45 of the end walls 21, and the front section 47 of the top wall 19, are all rigidly secured together to form a cover unit 55 which is removably secured to the base unit.

70 In accordance with the present invention, I provide an upright slidable connecting means between the front and rear sections of each end wall, which means is so constructed as to provide for the removal and replacement of the cover unit 55 on the base unit 50 only by raising and

lowering movements of the cover unit. One reason for this form of connecting means is to assure at all times the proper relative position of the cover and base units when they are assembled. To this end, the rear part of the forward sections 45 of the end walls 21 are respectively provided with vertically disposed angle members 56 having flanges 57 extending inwardly toward the casing. The angle members 56 may be suitably spot welded to the forward sections 10 45. The rear sections 46 of the end walls are respectively provided with outwardly extending vertical flanges 58 which, when the cover unit is placed on the base unit, are disposed at the forward sides of the adjacent flanges 57. This construction and arrangement of the flanges provides in itself a slidable connection between the cover and base units. However, in order to prevent any forward and backward movement of the cover unit 55 when in position on the base unit 20 50, I provide vertical channel members 60 at the rear of the flanges 58 which form with the latter vertical grooves 61 for receiving the flanges 57. In addition to forming one side of the grooves 61, the channel members 60 slidably receive the adjacent sides of the filler blocks 15.

From the above description, it will be apparent that the cover unit can be removed and replaced upon the base unit only by raising and lowering the cover unit and permitting the flanges 57 to slide vertically in the grooves 61, as can be readily seen from an examination of Figs. 3 and 7. When the cover unit is lowered into position on the base unit, it is firmly secured thereto by means of screws 62 passing through registering 35 openings in the lower rear part of the forward sections 45 and in an upstanding flange 63 on the forward half of the base unit 50. Suitable blocks 64 are spot welded to the inside of the flange 63 of the base unit, and provide screw-threaded 40 openings of sufficient depth to hold the screws 62. At the lower central part of the front wall 17 of the casing, the cover unit is further secured to the upstanding flange 63 by means of a screw 65 passing through aligned openings in the lower part of the front wall 17 and in the upstanding flange 63 on the bottom wall 20, and a suitable block 66 is also spot welded to the upstanding flange 63 for the purpose of providing a screw-threaded 45 opening of sufficient depth to securely hold the screw 65.

An angle member 70 is spot welded to a downwardly turned flange portion 71 at the rear of the front section 47 of the top wall, and provides a longitudinally extending ledge 72 on which the forward part of the hinged rear section 48 of the top wall rests, and also provides a downwardly and rearwardly extending flange part 73 to which the upper part of the partition 28 is suitably secured by means of screws 74. A longitudinally extending angle member 75 is suitably spot welded to the forward part of the hinged rear section 48, and a sealing strip 76 of any suitable material is secured to a horizontal flange 77 of the angle member 75 and provides a sealing surface 55. against which the sill rail 11 engages. A vertical flange 78 of the angle member is arranged at the forward side of the lower sash rail 11.

The lower part of the partition 28 is provided with a removable panel section 80 secured at the top thereof by screws 81 to the remaining 70 parts of the partition and by the screws 37 to the brackets 38 which are carried by the removable base member 33, the latter carrying the motor-driven blower unit 31. On the rear face 75 of the removable panel section 80 are suitably

mounted electrical control elements for effecting and controlling the operation of the motor-driven blower unit. These elements may be of any type. They are here shown to be a resistor 83, a switch 84 and an outlet 85 for receiving a cord for attachment to a suitable electrical outlet in the room (not shown). The switch 84 is provided with an operating shaft 86 which extends forwardly through an opening in the removable panel portion 80. The forward end of the shaft 86 is squared and slidably receives the rear squared end of a removable shaft extension 87. The extension 87 extends forwardly through an opening in the front wall of the casing and is provided at its forward end with a reduced squared section 88. An operating knob 89 is provided with a squared recess 90 in its rear inside surface which fits over the squared outer end 88 of the removable extension section 87 and a screw 91 extending longitudinally through the knob 89, shaft extension 87, and engages a screw-threaded opening in the switch shaft 86, thereby serving to secure the operating knob in position on the shaft extension.

25 Thus, when it is desired to remove the cover unit 55, the screw 91 and the operating knob 89 are removed and the shaft extension 87 readily withdrawn through the opening in the front wall 17. The screws 62 and 65 may then be removed, the window sash raised, and the hinged rear section 48 swung rearwardly out of the way. The screws 14 may then be removed and the cover unit 55 may then be raised vertically from the base unit 50, the flanges 57 sliding upward in the grooves 61 provided on the base unit 50.

With the cover unit removed, if all that is needed is to make minor repairs to the electrical control devices, the lower panel 80 of the partition may be readily removed by removing the 40 screws 81 and 37. The control devices can then be exposed and minor repairs made thereto. Also, the working parts of the motor-driven blower unit can be oiled, if need be. However, if there need be major repairs to the interior 45 working parts of the ventilator, the wing nuts 39 are removed and the motor-blower unit 31, along with the partition 28, removed bodily from the casing. The cover 55 may then be replaced and the sash rail lowered and the motor-blower 50 partition unit carried away to a service station where it can be repaired.

As the rear sections 46 of the end walls 21 are set inwardly with respect to the plane of their respective front sections 45, and as the 55 channels 60 for connecting the adjacent sides of the filler blocks to the casing are secured to the rear sections and thereby disposed inwardly of the planes of the front sections, the joints between the channels and casing and the major 60 portions of the channels are concealed from view from the front of the casing, and thereby do not detract from the neat and pleasing appearance of the casing when installed.

As the rear section 48 of the top wall is 65 displaced downwardly from the plane of the front section 47 thereof, and is provided at its forward edge with the angle member 75 having the vertical flange 78 which is disposed at the room side 70 of the sash rail, an effective weather-tight seal is provided between the lower sill rail 11 and the top wall 19 which provides for the effective draining of rain water, snow, etc., from the rear of the casing. The rear section 48 is formed with a 75 rearward slope, as shown, and thereby also aids

in effectively draining rain water from the top of the casing.

What I claim and desire to secure by Letters Patent of the United States is:—

1. A ventilator of the type adapted to be 5 mounted over a sill of a window with a front part facing the room and a rear part facing the outside, comprising a casing including front, rear, bottom, top and end walls; the top wall and the end walls being each divided to provide separable 10 front and rear sections; the rear sections of the top and end walls, respectively, the rear wall, and the bottom wall being secured together to form a base unit adapted to be fixedly secured in position on a window sill; the front sections of 15 the top and end walls, respectively, and the front wall being secured together to provide a removable cover unit; and an upright slidable connecting means between adjacent parts of the front and rear sections of each end wall and so constructed as to provide for removal and replacement of the cover unit on the base unit only by raising and lowering the cover unit with respect to the base unit.

2. A ventilator of the type adapted to be 25 mounted over a sill of a window with a front part facing the room and a rear part facing the outside, comprising a casing including front, rear, top, bottom, and end walls; the end walls and the top wall being each divided to provide front 30 and rear sections; the rear sections of the end walls and the top wall, respectively, the rear wall and the bottom wall being secured together to form a base unit adapted to be fixedly mounted on a window sill; the front sections of the end walls and the top wall, respectively, and the front 35 wall being secured together to form a removable cover unit; means providing an upright tongue-and-groove connection between adjacent portions of the front and rear sections composing 40 each of the end walls and constructed so that the cover unit may be removed and replaced only by raising and lowering the cover unit with respect to the base unit.

3. In a ventilator of the type adapted to be 45 mounted over a sill of a window with a front part facing the room and a rear part facing the outside, comprising a casing including front, rear, top, bottom, and end walls; the end walls and the top wall being each divided to provide 50 front and rear sections; the rear sections of the end walls and the top wall, respectively, the rear wall and the bottom wall being secured together to form a base unit adapted to be fixedly mounted on a window sill; the front sections of the end 55 walls and the top wall, respectively, and the front wall being secured together to form a removable cover unit; means providing an upwardly extending groove on the forward part of each of the rear sections of the end walls and 60 opening in a direction extending away from the plane of its respective rear section; means providing an upright tongue member on the rearward part of each of the front sections of the end members; the tongue members being arranged to slidably fit within the adjacent grooves and providing for removal and replacement of the cover unit only by raising and lowering movements of the cover unit.

4. A ventilator of the type adapted to be 70 mounted over a sill of a window with a front part facing the room and a rear part facing the outside, comprising a casing including front, rear, bottom, top and end walls; the top wall and the end walls being each divided to provide separable 75

front and rear sections; the rear sections of the top and end walls, respectively, the rear wall, and the bottom wall being secured together to form a base unit adapted to be fixedly secured in position on a window sill; the front sections of the top and end walls, respectively, and the front wall being secured together to provide a removable cover unit; the rear section of each end wall being arranged inwardly of the plane of the adjacent front section and being provided at its forward edge with an outwardly extending flange; the front section of each end wall being provided at its rearward edge with an inwardly directed flange arranged at the rearward side of the flange on the adjacent rear section so as to provide a sliding connection therebetween which provides for the removal and replacement of the cover unit on the base unit only by raising and lowering the cover unit.

5. A ventilator of the type adapted to be mounted over a sill of a window with a front part facing the room and a rear part facing the outside, comprising a casing including front, rear, bottom, top and end walls; the top wall and the end walls being each divided to provide separable front and rear sections; the rear sections of the top and end walls, respectively, the rear wall, and the bottom wall being secured together to form a base unit adapted to be fixedly secured in position on a window sill; the front sections of the top and end walls, respectively, and the front wall being secured together to provide a removable cover unit; the rear section of each end wall being set inwardly of the casing from the plane of the front section thereof; and means for detachably securing the cover unit to the base unit.

6. A ventilator of the type adapted to be arranged within a window opening defined by a lower sill rail of a partially raised window sash, a window sill and window jambs, comprising a casing adapted to be mounted over the window sill and having a front portion arranged at the inside of the window sash and a rear portion at the outside of the window sash; said casing comprising front, rear, top, bottom, and end walls; each of the end walls comprising a front section and a rear section joining the front section along an upright line and being displaced inwardly of the casing from the plane of the front section; and upright filler blocks of substantially the same height as the casing and closing the spaces between each end wall and the adjacent window jambs; the side of each filler block which is disposed adjacent an end wall of the casing being arranged immediately to the rear of the front section thereof and being secured to the forward end of the rear section thereof; and means providing a sealing connection between the lower sash rail and the top of the filler blocks and the casing top wall.

7. A ventilator of the type adapted to be arranged within a window opening defined by a lower sill rail of a partially raised window sash, a window sill and window jambs, comprising a casing adapted to be mounted over the window sill and having a front portion arranged at the inside of the window sash and a rear portion at the outside of the window sash; said casing comprising front, rear, top, bottom and end walls; each of the end walls comprising a front section and a rear section displaced inwardly of the front section and joining the latter along an upright line just forward of the plane of the window sash; the top wall comprising a front section and a rear

section joining the front section just forward of the plane of the window sash and being displaced downwardly from the plane of the front section of the top wall; upright filler blocks of substantially the same height as the casing and closing the space between each end wall and the adjacent window jamb; the side of each filler block which is disposed adjacent an end wall of the casing being arranged immediately to the rear of the front section thereof and being secured to the forward end of the rear section thereof; and means providing a sealing connection between the lower sash rail and the top of the filler blocks and the forward part of the rear section of the top wall.

8. A ventilator of the type adapted to be arranged within a window opening defined by a lower sill rail of a partially raised window sash, a window sill and the window jambs, comprising a casing adapted to be mounted over the window sill and having a front portion thereof arranged at the inside of the window sash and a rear portion thereof at the outside of the window sash; said casing comprising front, rear, top, bottom and end walls; each of the end walls being divided along an upright line to form a front section including an inwardly directed flange along its rearward edge, and a rear section set inwardly from the plane of the front section and having an outwardly directed flange along its forward edge arranged at the forward side of the first-named flange; the lines of division between sections of the end walls being at substantially the same distance from the front wall; the top wall being divided longitudinally into a front section and a rear section; the rear sections of the top and end walls, respectively, the rear wall and the bottom wall being secured together to form a base unit adapted to be fixedly secured in position on a window sill with the overlapping flanges arranged slightly forward of the window sash; the front sections of the top and end walls, respectively, and the front wall being secured together to provide a removable cover unit; an upright channel member secured to the forward part of the rear section of each end wall and being arranged in parallel spaced relation to the flange thereon so as to provide therewith an upright groove for receiving the flange on the adjacent front section and providing a slidable connection between the cover unit and the base unit; upright filler blocks of substantially the same height as the casing and closing the spaces between the end walls and the adjacent window jambs, and having the sides thereof adjacent the end walls disposed within the channels carried thereby; and means providing a sealing connection between the lower sash rail and the top of the filler blocks and the forward part of the rear section of the top wall.

9. A ventilator of the type adapted to be mounted over a sill of a window with the front part facing the room and the rear part facing the outside, comprising a casing including front, rear, bottom, top and end walls; each of the end walls being divided along an upright line into a front section and a rear section, with the latter being displaced inwardly of the casing from the plane of the front section and with the lines of division of both end walls at substantially the same distance from the front wall; the top wall being divided into a front section and a rear section with the line of division being substantially parallel to the front wall and spaced from the front wall substantially the same distance as the lines

of division of the end walls; the rear section of the top wall being displaced downwardly from the plane of the front section; the rear sections of the top and end walls, respectively, the rear wall and the bottom wall being secured together to form a base unit adapted to be fixedly secured in position on the window sill; the front sections of the top and end walls, respectively, and the front wall being secured together to provide a removable cover unit; and means for detachably securing the cover unit to the base unit.

10. A ventilator of the type adapted to be mounted over a sill of a window with a front part facing the room and a rear part facing the outside, comprising a casing including front, rear, bottom, top and end walls; the top and the end walls being each divided to provide separable front and rear sections; an upright partition arranged lengthwise of the casing and dividing the latter into a rear air chamber and a front air chamber; a motor-blower unit arranged within one of said chambers and operating to force air through said casing for ventilating the room; means for detachably securing the partition and motor-blower unit to the bottom wall of the casing; the rear sections of the top and end walls, respectively, the rear wall, and the bottom wall being secured together to form a base unit adapted to be fixedly secured in position on a window sill; the front sections of the top and end walls, respectively, and the front wall being secured together to provide a removable cover unit; an upright slideable connecting means between adjacent parts of the front and rear sections of each end wall and so constructed as to provide for removal and replacement of the cover unit on the base unit only by raising and lowering the cover unit with respect to the base unit; and means for detachably securing the rear part of the front section of the top wall to the upper part of the partition, and for detachably securing the lower part of the cover unit to the bottom wall of the casing.

11. A ventilator of the type adapted to be mounted over a window sill with a front part facing the interior of a room and a rear part facing the outside, comprising a casing including a base unit and a removable cover unit; the base unit being fixedly secured to the window sill and including a bottom wall and a rear wall secured to one another; the cover unit including a front wall and a top wall part secured together and detachably secured to the base unit; an upright partition extending lengthwise of said casing and dividing the interior thereof into a rear inlet chamber and a front outlet chamber; said partition including a removable panel portion; means accessible from said inlet chamber for detachably securing the panel portion in position; a motor-blower unit in said rear inlet chamber; and electrical devices carried by the rear side of said removable panel portion for effecting and controlling the operation of said motor-blower unit.

12. A ventilator of the type adapted to be mounted over a sill of a window with a front part facing the room and a rear part facing the outside, comprising a casing including front, rear, bottom, top and end walls; the casing having an air opening in the rear part thereof and an air opening in the front part thereof; an upright partition extending lengthwise of said casing and dividing the interior thereof into a rear air chamber and a front air chamber; said partition including a removable panel portion; means accessible from the front air chamber for detachably securing

the removable panel portion in position; a motor-blower unit arranged within the rear air chamber, and being operable to draw air in through one of said openings and force such air through the other of said openings; electrical devices carried by the rear side of said panel portion for effecting and controlling the operation of said motor-blower unit; the casing top wall and the casing end walls being each divided to provide separable front and rear sections; the rear sections of the top and end walls, respectively, the rear wall, and the bottom wall being secured together to form a base unit adapted to be fixedly secured in position on a window sill; the front sections of the top and end walls, respectively, and the front wall being secured together to provide a removable cover unit; and means for detachably securing the cover unit to the base unit.

13. A ventilator of the type adapted to be mounted over a window sill with a front part facing the interior of a room and a rear part facing the outside, comprising a casing including a base unit adapted to be fixedly secured to the window sill and a front removable cover unit; upright slideable connecting means between adjacent parts of the base unit and cover unit and so constructed as to provide for removal and replacement of the cover unit on the base unit only by raising and lowering the cover unit with respect to the base unit; the base unit including a bottom wall and a rear wall secured to one another; the cover unit including a front wall and a top wall part secured to one another; a motor-blower unit arranged within said casing and operating to move air through said casing and ventilate the room; a switch fixedly secured inside of said casing for controlling the operation of said motor-blower unit and including an operating shaft having a removable extension extending forwardly and exteriorly of said casing through said front wall; and an operating knob at the outside of said front wall and detachably secured to the outer end of the removable extension.

14. A ventilator of the type adapted to be mounted over a window sill with a front part facing the interior of a room and a rear part facing the outside, comprising a casing including a base unit adapted to be fixedly secured to the window sill and a removable front cover unit; upright slideable connecting means between adjacent parts of the base unit and cover unit and so constructed as to provide for removal and replacement of the cover unit on the base unit only by raising and lowering the cover unit with respect to the base unit; the base unit including a bottom wall and a rear wall secured to one another; the cover unit including a front wall and a top wall part secured to one another; an upright partition extending lengthwise of said casing and dividing the interior thereof into a rear inlet chamber and a front outlet chamber; said partition including a removable panel portion; means accessible from said inlet chamber for detachably securing the panel portion in position; a motor-blower unit in said rear inlet chamber; an electrical switch carried by the removable panel portion at the rear side thereof for controlling the operation of said motor; said switch including an operating shaft extending forwardly through the removable panel and having a removable extension extending forwardly through the inlet chamber and through the front wall of the casing; and an operating knob at the front side of said front wall and detachably

secured to the outer end of the removable extension of the switch-operating shaft.

15. A ventilator of the type adapted to be mounted over a sill of a window with a front part facing the room and a rear part facing the outside, comprising a casing including front, rear, bottom, top and end walls; the casing having an air opening in the rear part thereof and an air opening in the front part thereof; the top wall 10 and the end walls being each divided into separate front and rear sections; the rear sections of the top and end walls, respectively, the rear wall, and the bottom wall being secured together to form a base unit adapted to be fixed in position on a window sill; the front sections of the top and end walls, respectively, and the front wall being secured together to provide a removable cover unit; means for detachably securing the cover unit to the base unit; a motor-blower unit 15 removably mounted in said casing and operable to draw air through one of said air openings and force such air through the other of said air openings; said motor-blower unit being supported by said bottom wall and including that 20 part of the bottom wall which extends forwardly of the rear sections of said top and end walls, so that said motor-blower unit may be removed from the front when said cover unit is removed and without disturbing the mounting of said base 25 unit; and means accessible when said cover unit

is removed for detachably securing said motor-blower unit to said bottom wall.

16. A ventilator of the type adapted to be mounted over a sill of a window with a front part facing the room and a rear part facing the outside, comprising a casing including front, rear, bottom, top and end walls; the top and the end walls being each divided into separate front and rear sections; an upright partition arranged lengthwise of the casing and dividing the latter 10 into a rear air chamber and a front air chamber; a motor-blower unit arranged within one of said chambers and operable to force air through said casing for ventilating the room; means for detachably securing the partition and motor-blower unit to the bottom wall of the casing; the rear sections of the top and end walls, respectively, the rear wall, and the bottom wall being secured together to form a base unit adapted to be fixed in position on a window sill; the front 20 sections of the top and end walls, respectively, and the front wall being secured together to provide a removable cover unit; and means for detachably securing the cover unit to the base unit and including means for securing the rear part 25 of the front section of the top wall to the upper part of the partition, and for securing the lower part of the cover unit to the bottom wall of the casing.

FRANCIS C. KILB. 30
